RALPH A. NORQUIST AND GLENN H. NORQUIST, OF JAMESTOWN, NEW YORK

WINDOW SCREEN

Application filed March 19, 1929. Serial No. 348,285.

This invention relates to metal frame window screens and has special reference to the structure whereby a seat for the screen wire is provided and the screen is secured to the seat. The object of the invention is to provide a durable window screen which will have leak-proof joints and may be economically produced, the structure being such that the screen will be firmly secured in a taut smooth 10 condition but may be readily removed when a broken screen is to be replaced. The invention is illustrated in the accompanying drawing and consists in certain novel features which will be particularly defined following 15 a detailed description.

In the drawing:

Figure 1 is a sectional perspective view of a window screen embodying the invention;

Fig. 2 is an enlarged elevation of one corner of the screen showing the meeting members of the frame partly separated and partly broken away and in section;

Fig. 3 is a detail section on the line 3-3 of Fig. 2;

Fig. 4 is a detail section illustrating a step in the manufacture of the frame, and

Fig. 5 is a detail section showing a modified form of locking strip or key.

According to the present invention, the 30 frame is constructed of sheet metal, the stiles and top and bottom rails being produced in long strips and then cut to size according to the dimensions of the screen which is to be eventually produced. The blank from which 35 the stile or rail is to be produced is passed successively through dies or shaping rolls and when it emerges from the final dies or pair of rolls will have the form shown clearly in Figs. 3, 4, and 5 of the drawing. As thus produced, the frame bar comprises a base web 1 having an integral inwardly projecting central U-shaped offset 2 extending longitudinally the entire length of the bar, the offset 2 constituting a grooved rib adapted to engage the mating rib 3 of a track 4 which is secured to the side member of the window frame. The stile at one side of the finished screen has this rib or shoe 2 of comparatively slight depth, as shown in Fig. 4, while at the 50 other side the rib is elongated, as shown at 5

in Fig. 3, whereby it may engage a somewhat higher track rib 6 secured to the opposite side of the window frame, and a leaf spring 7 is secured within this deeper track rib or shoe 5, as shown in Fig. 2, to facilitate the fitting of the screen to the window frame in the usual manner. Extending from the side edges of the base member 1 are parallel side plates 8 and one side plate is doubled upon itself, as shown at 9, whereby the edge of the frame bar is reinforced and buckling is prevented. From the inner edge of the doubled reinforcement 9, the plate extends transversely of the frame bar to form a bridging member 10 which abuts the parallel side plate and then extends inwardly toward the free edge of said parallel side plate for a short distance, as shown at 11, to form a seat for the screen and the locking rib or key. The longer plate 8 extends across and beyond the seating member 11 to constitute a reinforcement, and from the inner edge of said seat the metal plate is carried transversely at an angle to said longer side plate and to the bridging member 10, as shown at 12, this portion 12 extending approximately one-half the width of the frame bar. The side plate and the inner plate then extend inwardly in parallelism for a short distance, as shown at 13, the edge portion of the side plate being bent inwardly to produce a beveled or inclined portion 14 terminating in an inturned lip 15 which is disposed in the same plane as the portion 13, as shown clearly in Fig. 4. Said portion 13 is slightly offset, as indicated at 16, whereby its edge portion may extend between the lip 15 and the oblique or beveled portion 14 with its extreme edge folded on itself to bear against the said oblique or beveled portion. Prior to the entrance of the blank between the finishing dies or rolls, a strip of solder, indicated at 17, is introduced between the inwardly extending intermediate web 13 and the obliquely disposed web 14 so that when the lip 15 and the mating edge portion of the web 13 are bent together by the dies or rolls the solder will be housed, as indicated in Fig. 4, the frame being then held in the position shown in said figure so that heat which is then applied will melt the solder and cause 55 60 65 70 75 80 85 90 95 100

it to run down into and penetrate the joint formed by the members 13 and 15 whereby these members will be sweated together and permanently and rigidly united. The frame bar thus produced is very rigid and is free of open joints into which moisture or dust may penetrate to corrode the metal or to loosen the frame or cause other distortion or defects which will shorten the life of the screen. It may sometimes be desirable to invert the frame bar from the position shown in Fig. 4 so that the solder may be permitted to penetrate the joint between the longer side plate 8 and the seat portion 11 which abuts the same so that spreading of the side plates will be positively prevented. The seat 11 and adjacent portion of the plate 8 may be joined by spot-welding, if preferred.

Referring particularly to Fig. 3, it will be noted that the deeper shoe or track engaging member of the frame has side portions parallel with the side plates of the frame bar connected at their inner ends by an integral bridging web 18 and at the mouth or opening of this member are inwardly projecting opposed lips 19 formed by doubling the folds of the metal upon themselves so that the needed strength at this point will be attained. These lips 19 also furnish fulcrum ribs permitting the screen to rock upon the higher track rib 6 when the rib is being placed in a window or removed therefrom without bending or distorting either the track rail or the frame. Upon reference to Fig. 2, it will be noted that one end of the spring is turned at a right angle to project through an opening in the web 18 and thereby anchor the spring so that it cannot slide along the bar. As shown in Fig. 1, the width of the spring is somewhat greater than the distance between the lips 19 so that the lips prevent the spring flying from the bar and thereby being lost. At the same time, by grasping the bar midway its ends, the lips may be sprung apart sufficiently to permit the spring to be removed and inserted if necessary.

The wire netting 20 which constitutes the screen proper has its edge placed over the shelf or rail produced by the lip 15 and the web 13 alined therewith and folded into the seat presented by the portions 10 and 12 and the intermediate connecting web 11, the doubled lip 9 constituting a shoulder overhanging the seat 11, as shown and as will be understood. A locking strip or key 21 is then engaged with the shoulder 9 and the screen seat so that the screen will be stretched taut and smooth and firmly secured. In Figs. 1 and 3, the key is shown as consisting of a strip of metal V-shaped in cross section and having its shorter branch or web fitting between the shoulder 9 and the seat 11 and against the surface of the wire netting. The key is placed in position by having its angle en-

gaged under the overhanging shoulder 9 and is then rocked so that its shorter side will enter the seating portion of the frame and pull the netting closely into the same, the longer web or branch of the key assuming an oblique position with its free edge bearing upon the netting and clamping the same to the lip 15. The key will thus be very firmly secured in place so that it can not be dislodged under ordinary usage but if the wire netting should be damaged, so that it must be renewed or replaced, a flat-ended pry of any convenient type, such as a screw driver, may be engaged under the edge of the outer longer member of the key and the key then pried from under the shoulder 9 so as to release the netting. The key is resilient so that it may be easily made to clear the netting engaging surfaces of the frame and will immediately resume its normal form after being released so that the forcing of the key into place or the removing of the same as is occasionally necessary will not permanently distort the key.

It will be particularly noted that when the key has been forced home its angle will engage in the angle formed by the overhanging shoulder 9 and the transverse bridging web 10 while the edge of its shorter branch or member will clamp the wire netting in the inner angle of the seat 11. The angular disposition of the wall 12 causes the inner member of the key to wedge in its seat when forced home, whether it bears upon the bottom of the seat or the wall 12, so that the outer web of the key will bear tightly upon the screen netting. And it may be noted at this point that this method of fastening may be employed to secure glass panes, cloth, metal, or other panels.

If a heavier frame be desired, the key shown in Fig. 5 may be used, the outer member 22 of this key corresponding in all respects to the outer member of the key shown in Fig. 3. The inner member, however, is formed with a short portion 23 which is adapted to extend parallel with the bridging web 10 and then is formed into a bead 24 which substantially fills the seating space defined by the webs 10, 11 and 12 so that the screen will have additional bearing and gripping portions. This key is inserted and removed in the same manner as the first described key.

When the bar is cut into lengths to form the stiles and end rails of the screen frame, the cuts are at an angle of forty-five degrees to the sides of the bar, as shown at 25, so that when the bars are brought together they will form a miter joint, and to produce permanent rigidity in the frame and prevent separation of the members thereof at the joints the mating joint edges may be brazed or welded together. To further reinforce the corners of the frame, a bracing rod 26 is engaged in the openings defined by the portions 14, 15 130

and 13, as shown most clearly in Fig. 3, and an additional brace 27 may be engaged in the open ends of the shoes or track-engaging portions of the bars, sufficient clearance for the 5 reception of the braces being left between the inner and outer webs of the bar shown in Fig. 3. The braces 26 and 27 are both of right angular formation, as shown clearly in Fig. 2, and the brace 27 may be U-shaped in cross section, as shown in Fig. 3, so that it will fit closely to the side plates and the bridging element 10 of the frame bar, being housed between the track shoe and the side plates of the frame bar at the spring-carrying side of 10 the frame.

Rollers may, if desired, be mounted in the stiles to engage and run on the respective tracks. The lips 19 fit close to the track 6 so that screens in a double-track structure may 15 easily pass each other.

A screen frame constructed as herein described is exceedingly strong and durable and can be produced at less cost than other metal screen frames now known to us.

Having thus described the invention, we claim:

1. A frame for window screens consisting of hollow metal bars having mitered meeting ends and each having a longitudinally extending hollow shelf against which a screen may be seated, a right angular reinforcing rod having its branches engaged in the open ends of meeting shelves, and means for clamping a screen to the shelves.

2. A frame for screens consisting of hollow metal bars having track-engaging shoes formed in their outer longitudinal edges and having hollow screen supporting shelves along their inner edges, said bars having mitered meeting ends, means for clamping a screen to the shelves, and right angular reinforcements fitted in the outer hollow portions of the bars around the shoes at their meeting ends.

3. A screen frame comprising hollow frame bars each constructed of a single strip of metal having parallel side portions with one side portion extending beyond the other side portion at its free edge, and a bridging portion extending between the side portions and having a free edge portion offset from the wider side portion, the wider side portion having its free edge doubled inwardly on itself to overhang and bear against the extreme free edge of the bridging portion and defining a hollow screen-supporting shelf, and means within the shelf embedding said free edge portions whereby to permanently secure the same together, the shelf and the 50 opposite side portion of the frame bar forming a groove to receive an edge of the screen material and a locking key.

4. A screen frame consisting of hollow metal frame bars each formed into parallel side plates having their outer longitudinal

edges integrally connected by a track-engaging element, one side plate having its terminal inner edge portion formed into an obliquely disposed web and a lip extending inwardly from said web in a plane between and parallel with the planes of the side plates and the other side plate having its inner edge portion doubled backwardly upon itself to produce an overhanging reinforcing shoulder, a bridging portion extending transversely between the side plates at the outer side of said shoulder, then extending inwardly in contact with the first-mentioned side plate to form a screen seat, and then offset and extended forwardly to engage behind the lip and to form a hollow screen-supporting shelf, said shelf, reinforcing shoulder and bridging portion defining a groove to receive an edge of screen material and a locking key.

5. A screen frame comprising hollow metallic frame-bars each constructed at its inner longitudinal edge between its sides with a transverse bridging web, an overhanging inwardly projecting shoulder at one side of said web, a screen seat at the opposite side of said bridging web, a flat hollow offset screen-supporting shelf extending inwardly from the seat in a plane parallel with and between the sides of the bar, and a resilient locking key engageable at one side in the seat and under said overhanging shoulder and bearing at its outer edge against the shelf whereby to scratch the screen over the shelf to clamp it in the seat.

6. A screen frame comprising hollow metallic frame bars each constructed at its inner longitudinal edge with a transverse bridging web, an overhanging inwardly projecting shoulder at one side of said web, a screen seat at the opposite side of said bridging web, a flat screen-supporting shelf extending inwardly from the seat between and parallel with the sides of the bar, and a resilient locking key engageable in the seat and under said overhanging shoulder and bearing at its outer edge against the shelf whereby to stretch and secure the screen over the shelf and in the seat, the inner portion of said key being constructed with a bead substantially filling the screen-receiving seat and holding the screen to all sides of the seat.

7. A screen frame including a frame bar having a track-engaging portion provided with opposed lips adapted to engage opposite sides of the track, and a leaf spring housed in the track-engaging portion and having one end engaged in an opening in the inner wall of said portion, the width of the spring being greater than the distance between the lips.

In testimony whereof we affix our signatures.
